UNITED STATES PATENT OFFICE.

ALBERT GOLDBERG, OF NEW ORLEANS, LOUISIANA.

FOLDABLE TABLE.

Application filed February 11, 1926. Serial No. 37,560.

This invention relates broadly to tables, but it more especially comprehends the foldable or collapsible type, and adaptable when folded or collapsed to a variety of uses.

5 An important object of this invention is to provide a combination device of this character which may be used as a card of Mah jongg table, as well as an ornamental smoking stand, flower pot stand, telephone stand, 10 or pedestal.

Another important object of this invention is to provide a combination device of this character, adaptable as an automobile tourist combination table and utensil case, constituting when folded a container in the nature of a suit case.

15 A further object of this invention is the provision of a foldable table and smoking stand, the table when folded adapted to contain 20 coal and support the stand top, thereby effecting a composite stand or pedestal.

With these and other objects in view, which will become apparent as the description proceeds, the invention resides in the 25 construction, combination and arrangement of parts, hereinafter more fully described and claimed, and illustrated in the accompanying drawings in which like characters of reference indicate like parts throughout 30 the several figures, of which:

Fig. 1 is a perspective view of my improved table folded and constituting in combination with a smoking stand, a pedestal or ornamental stand;

35 Fig. 2 is a perspective view of the smoking stand disassociated from the table;

Fig. 3 is a top plan view of the smoking stand and composite pedestal top;

40 Fig. 4 is a top plan view of the table in folded position with the top removed;

Fig. 5 is a bottom plan view of the table with the legs in folded position;

Fig. 6 is a side elevation of the table in 45 operative position;

Fig. 7 is a side elevation at right angles to Fig. 6 and showing leg braces in operative position;

Fig. 8 is a perspective view of a slightly modified form showing the table folded to 50 constitute a tourist's utensil case;

Fig. 9 is an end view of Fig. 8;

Fig. 10 is a bottom plan view of the table shown folded in Fig. 8 showing the utensil compartments and legs in folded position;

Fig. 11 is a side elevation of Fig. 10; and 55 Fig. 12 is a side elevation at right angles to that of Fig. 11.

In the illustrated embodiment characterizing this invention there is shown a foldable or sectional table top A formed with four 60 sections or leaves 1, 2, 3, and 4 hingedly connected by hinges 9, 10, and 11, and 21, 22, and 23, respectively, suitably secured to their under surfaces as clearly shown in Fig. 2 of the drawings. The said leaves are maintained in extended or open position by bar 17 pivoted substantially central of its length as at 18 and adapted to lockingly engage the oppositely extending cleats 16 and 19 suitably secured to leaves 1 and 4, respectively. 65

Suitably secured to leaf 4 spaced from the outer edge thereof is a longitudinally extending strip 7 to the outer side of which spaced from one end is pivotally secured the upper end of leg 5 in any suitable manner, 70 and in order to maintain the said leg in operative position at right-angles to said leaf, a foldable brace member 6 is provided. Similarly spaced and secured to the inner side of strip 7 at its other end is leg 8 provided with a foldable brace 20 similar to brace 6, as clearly shown in Fig. 6 of the drawings. Leaf 1 is formed identical to leaf 4 with anchoring strip 13 to one end of which is secured leg 15 and brace 14 and to 75 the opposite end, leg 12 and brace 24, said legs being shown folded in Fig. 5 and extended in Figs. 6 and 7. The operative positions of the foldable braces 14 and 24 are clearly shown in Fig. 6. 80

85 A diagonal folding brace 29 is pivotally secured to the upper end of leg 15 and its other end is adapted to hook or otherwise suitably engage a screw or other anchoring element secured to leg 5 spaced from its 90 lower end. A similar brace 30 is secured to the upper end of leg 8 and adapted to extend across and engage the anchoring element on leg 12, said braces effecting rigidity of the 95 leg supporting structure, and designed when not in use to fold parallel with the respective legs to which they are secured. 100

A smoking stand 25 formed with a top 26 carrying an ash tray 27 and a base 28, constitutes in combination with the table top 105 A when in folded position, a pedestal B, the top 26 forming the top of the said pedestal, as clearly shown in Fig. 1 of the drawings.

The table as above referred to is secured in folded position by a suitable fastening means 31 carried by the leaves 1 and 4.

The invention as above described may 5 with slight modification be utilized as a combination camping table and utensil container without affecting its primary use, by forming the leaves 2' and 3' with canvas or leatherette compartments 32 and 33 for holding 10 kitchen utensils, such as a frying pan 34 and forks, knives, spoons, etc. 35, respectively, and compartments 36 and 37 adapted to hold canned goods or other articles, all of said compartments being secured to the leaves in 15 any suitable manner.

While it is apparent that the smoking stand 25 may have its base 28 formed similar to top 26 so as to constitute ends when the table is folded for use as a container C; 20 in the present instance, the ends are formed of separate but similar pieces 38 to which are suitably fastened catches 39 designated to catch or snap over rods or anchoring elements 40 suitably secured to leaves 2' and 25 4' on opposite sides of the container to firmly maintain the said ends 38 in operative position.

In order to more firmly secure the leaves or sections 1', 2', 3', and 4' in folded position and to render portability of the container C easy, a strap and handle structure 41 is provided.

From the above it is apparent that I have 35 designed a combination table adaptable to a variety of uses, simple in construction, expeditiously convertible from one form to another, manufacturable at a reasonable cost, and yet efficient for the purposes intended.

Although in practice I have found the 40 form of my invention illustrated in the accompanying drawings and referred to in

the above description as the preferred embodiment, is the most efficient and practical; yet realizing the conditions concurrent with the adoption of my device will necessarily 45 vary, I desire to emphasize that various minor changes in details of construction, proportion and arrangement of parts, may be resorted to within the scope of the appended claims without departing from or 50 sacrificing any of the principles of this invention.

Having thus described my invention, what I desire protected by Letters Patent is as set forth in the following claim:

A combination foldable table, stand and container, comprising a plurality of hinged sections constituting a table top, a strip secured to each outer hinged section, a pair of legs pivotally connected to each strip and parallelly with respect thereto and underlying the respective sections, means for maintaining the legs in extended position, a cleat secured to each outer section substantially central of its length, a bar pivotally 65 secured to one of the central sections and engageable with said cleats to maintain said sections in the same plane, said sections being foldable at right angles to each other, whereby the outer sections carrying their 70 respective folded legs will contact each other at right angles to form a container, and closure members for said container, means carried by said members for detachable engagement with means carried by certain of 75 said hinged sections for securing said closure members thereto, whereby said container is converted into a stand, one of said members constituting a stand top and the other 80 a supporting base, and means for maintaining the hinged sections in folded position.

ALBERT GOLDBERG.
